UNITED STATES PATENT OFFICE.

EDWIN L. POWELL, OF WASHINGTON, DISTRICT OF COLUMBIA, ASSIGNOR TO WIRED RADIO, INC., OF NEW YORK, N. Y., A CORPORATION OF DELAWARE.

RADIO SIGNALING APPARATUS.

Application filed July 10, 1925. Serial No. 42,771.

My invention relates broadly to radio receiving apparatus and particularly to radio receiving apparatus using auxiliary local oscillating circuits to heterodyne with incoming radio signals, well-known in the art as heterodyning or superheterodyning.

The object of my invention is to provide a circuit to impress the heterodyning oscillations onto the received signals and at the same time to eliminate any detuning of the auxiliary oscillating circuit while tuning the incoming receiving circuits.

Further objects of my invention will appear more fully hereinafter.

My invention consists substantially in the construction, combination, and arrangement of parts and circuit arrangements associated therewith, all as will be more fully herein-after set forth as shown by the accompanying drawing and pointed out in the appended claims.

Reference is to be had to the accompanying drawing forming a part of this specification in which the figure represents a schematic diagram of my invention.

1, 2 and 3 represent a primary circuit of a radio receiver, 4 and 5 the tuned secondary circuit inductively connected thereto, 6 a stopping condenser, 7 a vacuum tube, and 8 a grid leak, all connected as shown and as is well-known in the art. Vacuum tube 9 has a tuned grid circuit made up of inductance 10 and condenser 11. Coupling of the plate circuit to the grid circuit is by means of coil 12. Coil 13 is a choke coil in the plate battery circuit to prevent the oscillations set up by tube 9 and associated circuits from passing through the plate battery. The feed-back circuit of the local oscillation tube, 40 which carries only the radio frequency component of the direct current in the plate circuit of tube 9, is completed to the filament from the low potential end of the tickler coil 12 through parallel paths, one leg of which is through condenser 14 and the other leg is through condenser 15 and grid leak 8. The vacuum tube 9 and associated circuits make up a generator of local oscillations to heterodyne with the received radio signals.

50 The principle of superheterodyne reception incorporates a first detector circuit tuned to the frequency it is desired to receive and a heterodyne oscillation circuit coupled thereto tuned to a higher or a lower frequency, the plate circuit of the first de-

tector being resonant to the difference of the frequencies or the beat frequency thus formed. This beat frequency is then amplified to the desired degree by means of a multi-stage intermediate frequency amplifier and again rectified by a second detector. For the reception of continuous wave signals a second local oscillating circuit is required for the production of audible beats.

Heretofore the adjustment of the super-heterodyne receiving apparatus for reception of continuous waves has been quite difficult, due to the fact that the first detector and heterodyning circuits were of necessity inductively coupled together and a reaction caused by the tuning of the first detector circuit dragged or varied the frequency of the heterodyne oscillator, resulting in a variation of the audible beats heard in the phones. This variation of the heterodyne frequency although not generally noticeable in the reception of damped or modulated signals, was so pronounced in the reception of continuous waves of supershort wave lengths, say 70 meters, that operation became impracticable and a new method of coupling and superposition was necessary to overcome this inherent fault in the superheterodyne system.

The novel feature of my invention is in the method of coupling the heterodyne oscillations to the incoming signals in the grid filament input circuit of the first detector tube. Instead of inductively coupling these oscillations to coil 2 or coil 4, as heretofore, the local oscillations are conducted direct to the grid of the first detector tube through one leg of the tickler feed back circuits previously mentioned, and thence along grid leak 8 to the filament; the desired local variations on the grid-filament input to the first detector tube 7 being made effective by the drop of potential across the grid leak 8. Complete elimination of reaction between the first detector and heterodyne oscillator tuned circuits is secured by reducing the usual resistance of grid leak 8 to a low comparative value, and employing comparatively high impedance values for the stopping condenser 6 and coupling condenser 15. The optimum values of these three units will be determined by the frequency band it is desired to cover, but for best operation their ratios, one to another, will remain practically constant for all frequencies. The capacity of the coupling

condenser 15, being once established for a given frequency band, the proportion of the total energy in the tickler circuit of the heterodyne tube required to be impressed on the first detector tube for optimum reception can be secured by a proper selection of the capacity of the condenser 14. Thus for a range of wave lengths of 70 to 300 meters, condenser 14 should be approximately .001 microfarad; condenser 15, 25 micro-micro-farads; grid leak 8, approximately one megohm; and condenser 6, approximately 25 micro-micro-farads. The value of the parts of all circuits is subject to variation to meet different conditions and is given here only to allow one familiar with the art to set up the required apparatus to determine the increased efficiency of this circuit arrangement.

The plate circuit of tube 7 is the usual superheterodyne arrangement of the first detector tube which by the proper selection of values of condenser 20 and inductance 21 is made to be resonant to the beat frequency formed by the incoming radio signals and the local oscillations generated in tube 9 and associated circuits. The beat frequency currents are conducted to an intermediate radio frequency amplifier through contacts 18, the transfer of energy being accomplished by the tuned circuit made up of inductance 16 and condenser 17.

It will be understood that the above description and accompanying drawing comprehend only the general and preferred embodiment of my invention and that various minor changes in detail, construction, proportion and arrangement of parts may be made within the scope of the appended claims and without sacrificing any of the advantages of my invention.

Having described my invention what I claim is:

1. In a signal receiving system a high fre-

quency energy collecting circuit, an electron tube detector having grid, filament and plate electrodes, input and output circuits interconnecting said electrodes with the input circuit thereof connected with said high frequency energy collecting circuit, an electron tube oscillator having grid, filament and plate electrodes, input and output circuits interconnecting said electrodes and coupled one to the other, a conductive connection between the plate electrodes of said detector and oscillator, a separate conductive connection between the filament electrodes of said detector and oscillator, a pair of condensers each having one side thereof connected to the output circuit of said oscillator and having the opposite sides thereof connected across the input circuit of said electron tube detector for impressing high frequency oscillations thereon while stabilizing the operation of said oscillator.

2. In a signal receiving system a high frequency energy collecting circuit, an electron tube detector having input and output circuits with the input circuit thereof connected with said high frequency energy collecting circuit, an electron tube oscillator comprising input and output circuits coupled one to the other, a common cathode circuit for each of said electron tubes, a common plate supply circuit for each of said tubes, a pair of independent condensers, a connection extending from said output circuit to a terminal common to said pair of condensers, the opposite sides of said condensers being connected to opposite sides of the input circuit of said electron tube detector, whereby oscillations generated and sustained by said last mentioned electron tube circuits may be impressed on the circuits of said electron tube detector at a frequency independent of the tuning of the input circuit of said electron tube detector.

EDWIN L. POWELL.
